UNITED STATES PATENT OFFICE.

CONSTANCE M. SKOLFIELD, OF NEW ORLEANS, LOUISIANA.

GAGE.

1,401,000.

Specification of Letters Patent. Patented Dec. 20, 1921.

Application filed November 8, 1920. Serial No. 422,575.

To all whom it may concern:

Be it known that I, CONSTANCE M. SKOLFIELD, a citizen of the United States, residing at New Orleans, in the parish of Orleans and State of Louisiana, have invented new and useful Improvements in Gages, of which the following is a specification.

This invention comprehends the provision of a sewing attachment, in the nature of a gage by means of which the depth of a tuck can be readily and easily determined, the gage including a movable element susceptible of adjustment so that a tuck of a proper width may be readily made.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views and where-

25 in:

Figure 1 is a top plan view of the attachment showing the same in position upon a machine for use.

Fig. 2 is a side elevation of the attachment.

Fig. 3 is an end elevation.

Fig. 4 is a transverse sectional view taken on the line 4—4 of Fig. 1.

Fig. 5 is a perspective view of the movable element.

The attachment forming the subject matter of my invention comprises an elongated member 10 which may be of any suitable material and of any desired dimensions, being preferably constructed of metal, however, and having a length of approximately five inches. The opposed longitudinal edges of the member are folded toward each other and are arranged in spaced relation to the body of the member to provide channels 11. The member 10 is provided with an elongated slot 12 arranged in a line with the longitudinal center of the member for a purpose to be hereinafter described. The member 10 is graduated along the opposed sides, as at 12'.

The gage proper is slidably mounted upon

the member 10 and comprises a body portion 13 which is vertically disposed above the member 10 and formed to provide horizontal L-shaped feet 15 which are slidably fitted within the channels 11. Projecting from the upper edge of the body portion 13 is a flange 16 arranged in parallelism with the member 10, and carried by said flange is a threaded element 18 adapted to be adjusted into contacting engagement with the plate of the sewing machine to hold the gage 13 fixed relatively to the member 10 in any of its adjusted positions.

In practice, the elongated member 10 is arranged upon the plate of the sewing machine. The member 10 may be held in this position by means of a fastening element 21 which passes through the slot 12 in the said member. Subsequent to the position of the member 10 in the manner stated, the gage 13 may be adjusted longitudinally of the member co-operating with the graduations thereon in order to position the gage 13 a requisite distance from the presser foot 20 for a tuck of a predetermined width. For instance, if it is desired to form a tuck on a piece of goods having a depth of two inches, the gage is moved along the member 10 until it is spaced two inches from the presser foot 20 of the machine. The adjustable element 18 is moved into engagement with the plate of the sewing machine to hold the gage fixed relatively to the member 10. The goods can then be readily folded to form the tuck and measured by the distance between the presser foot 20 and the gage 13. The attachment is very simple in construction, can be manufactured and sold at a nominal cost, and can be readily applied to any make of sewing machine.

While it is believed that from the foregoing description the nature and advantages of the invention will be readily apparent, I desire to have it understood that I do not limit myself to what is herein shown and described, and that such changes may be resorted to when desired as fall within the scope of what is claimed.

What I claim, is:

A sewing machine attachment comprising an elongated member removably secured to the machine, provided with a centrally dis-

posed longitudinal slot, bearing suitable indicia upon opposite sides of said slot and having the opposed longitudinal edges of said member folded inwardly to provide 5 channels, a vertical gage disposed above the elongated member and provided with horizontal L-shaped feet engaging said channels, a horizontal flange projecting from the upper edge of said gage, a threaded element carried by said flange extending through the slot in said elongated member and adapted to engage the plate of said machine.

In testimony whereof I affix my signature.

CONSTANCE M. SKOLFIELD.
